CLAIM

The ornamental design for a marking tape holder, as shown and described.

DESCRIPTION

FIG. 1 is a perspective view of a marking tape holder showing our new design;

FIG. 2 is a plan view thereof;

FIG. 3 is a front view thereof;

FIG. 4 is a bottom view thereof;

FIG. 5 is a rear view thereof;

FIG. 6 is a left side view thereof;

FIG. 7 is a right side view thereof;

FIG. 8 is a sectional view thereof taken along line 8—8 in FIG. 3; and,

FIG. 9 is a front view thereof with the cap removed for convenience of illustration.
